UNITED STATES PATENT OFFICE.

SAMUEL BONAT AND HARRY BONAT, OF NEW YORK, N. Y.

SPINDLE FOR PERMANENT HAIR-WAVING MACHINES.

Application filed September 25, 1926. Serial No. 137,650.

This invention relates to spindles for permanent hair-waving machines, and particularly to a spindle including an improved lock whereby the hair can be securely held.

5 In the permanent hair waving art a strand of hair is wound upon a spindle which is then inserted in a casing including a heating element. To secure satisfactory results and particularly to avoid pulling of the hair and 10 consequent discomfort during the winding and heating operation, the hair must be firmly held at one end of the spindle. Various forms of locks have been devised heretofore for the purpose but none fulfills the 15 requirements for a satisfactory device which is at the same time simple, inexpensive and easily operated.

It is the object of the present invention to 20 provide a spindle with a lock which can be manipulated easily to grip the hair firmly and to hold it securely until it is released.

Other objects and advantages of the invention will be apparent as it is better understood by reference to the following 25 specification and the accompanying drawing, in which

Fig. 1 is a view in perspective of a spindle with the lock thereon and illustrating the 30 use of the lock in securing the hair to the spindle;

Figs. 2 and 3 are plan views illustrating a 35 convenient form of the lock in closed and open positions;

Fig. 4 is a section on the line 4—4 of 40 Fig. 2;

Fig. 5 is a plan view of a slightly modified 45 form of the lock;

Fig. 6 is a side elevation of the lock as 50 shown in Fig. 5;

Fig. 7 is a plan view illustrating another 55 form of lock;

Fig. 8 is a similar view illustrating a lock 60 similar to that shown in Fig. 2 but with a modified form of aperture;

Fig. 9 is a plan view of a lock in which 65 the locking bar is secured in a slightly different way;

Fig. 10 is a side elevation of the lock as 70 shown in Fig. 9;

Fig. 11 is a plan view illustrating an alternative construction of the lock as shown in 75 Fig. 9;

Fig. 12 is a sectional view of the spindle with another form of the lock;

Fig. 13 is a plan view of another form 55 of lock; and

Fig. 14 is a section on the line 14—14 of Fig. 13.

In the preferred embodiment of the invention the spindle is provided with a head 60 having a pivoted locking bar secured thereto. The head is formed with a notch which is preferably V-shaped and the locking bar is adapted to be swung into position to close the notch and to secure the hair against the 65 inner edge of the notch. Owing to the V-shape of the notch the hair is firmly clamped by the locking bar which can be secured in locking position in a variety of ways. For example, the locking bar may be provided 70 with a screw at its end and a knurled nut can be mounted thereon so as to be moved into contact with the outer edge of the head. In modified forms the screw can be supported on the side of the head or on the 75 locking bar and the nut can be moved to cooperate with the locking bar or head respectively. Suitable notches may be provided in the head or locking bar to permit proper cooperation of the parts.

In another form of the invention either the locking bar or the head may be provided with ratchet teeth and a pawl on the corresponding part may cooperate with the teeth to hold the locking bar in proper position. In 80 this case there should be a resilient member to maintain the pawl and ratchet teeth in engagement until the locking bar is to be released.

In another form of the invention the 90 spindle may be hollow and the locking bar may extend therethrough, having at its end an eye or hook through which the strand of hair is threaded. When the locking bar is drawn into the spindle the strand is locked 95 against the end of the spindle which preferably is V-shaped to ensure that the hair is firmly held. The locking bar may have ratchet teeth adapted to cooperate with the

pawl on the spindle and springs may be provided to maintain the ratchet teeth in engagement with the pawl until the locking bar is to be released.

These and other modifications of the in-

vention will be readily understood from the following detailed description of the invention.

Referring to Figs. 1, 2, 3 and 4 of the drawing, 5 indicates a spindle having a head 6 secured thereto. The head is made preferably of two plates of generally circular form in spaced relation, the plates having a V-shaped notch 7 at one side. A locking bar 8 is pivoted at 9 between the two plates forming the head. The locking bar is adapted to be swung to open position as indicated in Fig. 3 and after the strand 9 of hair has been inserted in the notch 7 the locking bar is moved to the position indicated in Figs. 1 and 2 to firmly clamp the strand of hair in the notch. The locking bar 8 is provided with a threaded screw 10 at its free end and a knurled nut 11 is mounted thereon and is adapted to be moved into engagement with the edges of the two plates forming the head 6 to securely hold the locking bar 8 in locking position. Thereafter the strand of hair may be wound 25 upon the spindle 5 as indicated in Fig. 1 and the spindle may be inserted in the heating element (not shown).

In the modified forms of the invention as illustrated in Figs. 8 to 11 inclusive, the angle of the V-shaped notch 7 is somewhat more acute than in the forms of the invention previously described. The structure as shown in Fig. 8 is otherwise identical with that shown in Figs. 1 to 4 inclusive. In Figs. 9 to 11 inclusive a single plate 12 forms the head. In Figs. 9 and 10 a locking bar 13 is pivoted at 14 and is provided with a screw 15 carrying a knurled nut 16. The screw is adapted to enter a notch 16 in the head. The nut can be used to clamp the locking bar in the desired position. Fig. 11 illustrates an alternative form in which a single plate 17 carries a screw 18 and a knurled nut 19. The locking bar 20 is provided with a notch 21 which cooperates with the screw 18, the nut 19 being used as in the preceding forms of the invention to secure the locking bar in closed position.

In Figs. 5 and 6 of the drawing I have illustrated a lock comprising spaced plates 22 to which a locking bar 23 is pivoted at 24. The locking bar is provided with ratchet teeth 25 and when the locking bar is in closed position these teeth engage a pawl 26 on one of the plates 22. A spring 27 holds the pawl and ratchet teeth in cooperating relation so that the locking bar is firmly held. It can be released by depressing the spring 27 sufficiently to permit the teeth to escape from the pawl 26. In Fig. 7 a modification is illustrated in which a single plate 28 carries a pivoted locking bar 29. The plate 28 is provided with ratchet teeth 30 and a pawl 31 is formed on the locking bar

to engage the teeth. The locking bar may be made of any suitable material but it is preferably sufficiently resilient to maintain engagement between the pawl 31 and the ratchet teeth 30 until forcibly disengaged therefrom by the operator.

In Fig. 12 a hollow spindle 32 is provided and a locking bar 33 extends therethrough and is provided at its end with a hook 34 in which the strand of hair may be engaged. The end of the spindle is provided with a V-shaped notch 35 into which the strand of hair is drawn when the locking bar is moved to locking position. Ratchet teeth 36 are provided on the opposite end of the locking bar and are adapted to engage a pawl 37 on the spindle. Springs 38 hold the teeth 36 on the locking bar in cooperative relation with the ratchet. By flexing the springs the locking bar can be released to permit the withdrawal of the strand of hair from the hook 34.

In Figs. 13 and 14 the head consists of two spaced plates 39 having a notch 40 therein. A locking bar 41 is disposed between the plates and is provided at one end with a resilient pawl 42 which is adapted to engage teeth 43 on one of the plates 39. Thus one end of the bar is held in adjusted position. The other end is provided with a screw 44 carrying a knurled nut 45 which can be moved into engagement with the plates 39 to firmly hold the bar in the desired position. The strand of hair is disposed in the notch 40 and both ends of the locking bar are then adjusted to grip the strand of hair.

In the various forms of lock as described herein the manipulation required in order to secure the strand of hair is simple and sufficiently obvious so that it will be apparent even to relatively unskilled persons. Nevertheless the strand of hair can be firmly clamped and so held that the individual hairs cannot be pulled independently during the operation of winding the strand upon the spindle. The use of the lock as described ensures the most effective results with the greatest possible comfort.

Various changes may be made in the details of construction of the lock as described without departing from the invention or sacrificing any of the advantages thereof.

We claim:—

1. A spindle for permanent hair-waving machines comprising a mandrel, spaced plates with notches therein mounted on and permanently secured to the mandrel and forming a head therefor, a locking bar pivoted between the plates at one side of the notches and means at the other side of the notches to hold the locking bar in closed position.

2. A spindle for permanent hair-waving

machines comprising a mandrel, spaced plates with notches therein mounted on and permanently secured to the mandrel and forming a head therefor, a locking bar piv-

5 oted between the plates at one side of the notches, and means on the locking bar to cooperate with the head at the other side of

the notches to hold the locking bar in closed position.
In testimony whereof we affix our signa- 10
tures.

SAMUEL BONAT.
HARRY BONAT.
